BAG FOR CLOTHESPINS

John Fritiof Leonardson, Marinette, Wis.

Application December 6, 1934, Serial No. 756,269

2 Claims. (Cl. 248—99)

My invention relates to article containers and particularly to clothespin bags.

An object of my invention is to provide a clothespin bag which may be quickly and easily attached to a clothesline for support therefrom and sliding movement therealong.

Another object is to provide such a bag having means for preventing accidental detachment of the bag from a clothesline due to sudden or violent movement of the line.

Still another object is to provide such a bag which may be hung on a projecting element such as a peg or nail.

A further object is to provide such a bag whereof the hanger may be quickly, easily and inexpensively constructed of wire and which is rugged and durable.

These and other objects and advantages of the invention will be more fully apparent from the following description made in connection with the accompanying drawing, wherein like reference characters refer to the same or similar parts throughout the various views, and in which:

Fig. 1 is a front view of one form of my clothespin bag;

Fig. 2 is a side view;

Fig. 3 is a rear view of the upper portion of the hanger of a second form of my clothespin bag;

Fig. 4 is a vertical sectional view taken along the line 4—4 of Fig. 3 as indicated by the arrows;

Fig. 5 is a rear view of the upper portion of the hanger of a third form of my clothespin bag;

Fig. 6 is a vertical sectional view taken along the line 6—6 of Fig. 5;

Fig. 7 is a rear view of the upper portion of the hanger of a fourth form of my clothespin bag, and

Fig. 8 is a vertical sectional view taken along the line 8—8 of Fig. 7.

Referring to the drawing, and particularly to Figs. 1 and 2, B is a bag for clothespins or the like having a wide hem 10 at its upper edge to provide a sleeve or tunnel for receiving a ring. At diametrically opposite points the material forming the hem is cut away to provide openings affording access to the interior of the hem.

A bag supporting and distending ring 11 is formed of wire threaded through the interior of the hem. The two ends of the wire forming the ring are joined by twisting them together or by other suitable means at a point intermediate of the openings in the hem 10. At each of the

openings in the hem 10 the wire of the ring 11 is bent or wound through one complete circle to form loops 11a each of which lies in a plane tangent to the ring 11 and normal to the plane of the ring 11.

A hanger 12, formed of wire and shaped as shown in Figs. 1 and 2, has a pair of depending elements 12a terminating at their respective lower ends in eyes 12b linked with the respective loops 11a of the ring 11 to form swingable connections providing for tilting of the bag B relative to the hanger.

The hanger 12 has an upper portion 12c of W-shape connecting together the upper ends of the respective depending elements 12a as shown. At 15 the upper end center part of the upper portion 12c a loop 12d is formed. The portion 12c is disposed somewhat rearwardly of the depending elements 12a to form in conjunction therewith a hook-like structure including a hook element 20 formed at each of the junctions between the W-shaped portion and the respective ones of the depending elements 12a.

The hanger may be applied to a clothesline L or the like as shown in Figs. 1 and 2 or may be 25 hung on a nail or other projecting element by means of either the loop 12d or the crotch formed below the loop 12d.

Because of the swivel connection formed between the depending elements 12a and the ring 30 11 by means of the loops 11a and the eyes 12b the bag B may be readily tilted relative to the hanger to provide convenient access to the contents of the bag.

In the hanger of the second form of my bag, 35 shown in Figs. 3 and 4, the lower ends of the depending elements 13 are identical with those of the depending elements 12a of the first form and are connected to the rings 11 of the bag B in the same manner.

A W-shaped upper portion 14 is similar to the W-shaped upper portion 12c of the first form except that portions thereof are bent together as shown in Fig. 3 to form depending legs 14a which are bent forwardly and then rearwardly, as shown 45 in Fig. 4, to form knees 14b positioned forwardly of a plane common to the depending elements 13. Portions 14c of the hanger are disposed below the rope engaging hook-like uppermost part of the hanger to serve as rope retaining elements 50 capable of preventing detachment of the hanger from the clothesline L if the line L should be suddenly or violently moved.

Obviously the hanger may be hung upon a nail or other projecting element by means of the 55

crotch formed at its central uppermost portion.

In the hanger of the third form of my bag, shown in Figs. 5 and 6, the lower ends of the elements 15 are identical with the depending elements 12a of the first form and are attached to the ring 11 of the bag B in the same manner.

The upper portion of the hanger is formed as shown in Figs. 5 and 6 with a rope engaging or hook portion formed at the junction of each of the depending elements 15 with respective ones of two portions 16, portions 16 being disposed rearwardly of a vertical plane through a rope or clothesline L upon which the hanger is hung, portions 17 and 18 being disposed forwardly of that plane and the depending elements 15 being located still further forward.

A portion 19 connecting the lower ends of portions 16 and 17 and disposed directly below a clothesline L upon which the hanger is hung 20 functions as retaining means to prevent the hanger leaving engagement with the clothesline L should the clothesline be suddenly or violently moved.

In the fourth form of my bag the hanger, shown in Figs. 7 and 8, has depending elements 20 which are identical with the depending elements 12a of the first form and are attached to the ring 11 of the bag B in the same manner.

At the upper ends of the depending elements 20 the wire from which the hanger is constructed is bent to form portions 21, 22 and 23 respectively identical with the portions 16, 19 and 17 of the third form of my hanger. The middle portion of the hanger includes legs 14a bent forwardly and then rearwardly in the same manner as the legs 14a of the second form to form knees 25 and retaining portions 26 corresponding to the knees 14b and retaining portions 14c of the second form of my hanger.

It is to be noted that the portion 22 is directly below a clothesline L upon which the hanger is hung so as to confine the clothesline to prevent disengagement of the hanger from the clothesline if the same should be suddenly or violently moved. The retaining portions 26 prevent disengagement of the hanger from the line should side-ward movement of the line displace the same forwardly and downwardly from its normal position relative to the hanger.

Each of the four above described forms of my clothespin bag includes a hanger which engages a clothesline to which it is applied at two points and hence prevents twisting of the bag relative to the line. Also, each form is permissive of sliding movement of the bag along the clothesline.

Each of the second, third and fourth forms is easily attached to or detached from a clothesline but at the same time is constructed to prevent accidental detachment due to sudden or violent movement of the line.

Although Figs. 1 and 2 show a form of my clothespin bag having a hanger which does not include means for preventing accidental disengagement from the clothesline the preferred forms of my invention are those which include means for preventing accidental disengagement from a line such as shown in Figs. 3 to 8.

It is apparent that I have invented a novel, easily constructed, inexpensive and rugged clothespin bag adapted to be supported from a horizontal rope or line, adapted for easy engagement with or removal from such a line, permissive of sliding movement along such a line and yet arranged to prevent accidental detachment from such a line.

While my invention has been illustrated and described as a clothespin bag, it is obvious that my device is readily adaptable for uses other than containing clothespins.

It will, of course, be understood that various changes may be made in the form, details, proportions and arrangement of the parts, without departing from the scope of my invention, which, generally stated, consists in a device capable of carrying out the objects above set forth and in the novel parts and combinations of parts disclosed and defined in the appended claims.

What is claimed is:—

1. A hanger for supporting a clothespin bag or the like from an elongated horizontal element such as a clothesline comprising a pair of line engaging members disposed in respective planes substantially normal to a line upon which said hanger is hung and spaced apart along said line, each of said members consisting of an elongated relatively rigid element bent into a U-shape, one leg of the U being extended upwardly and bent to form a line engaging inverted hook above said U, the free end of said hook being extended diagonally downwardly and outwardly to extend past the upper end of the remaining leg of said U in sufficiently outwardly and upwardly spaced relation thereto to permit passage of said line therebetween, and a pair of relatively rigid vertical members connected at their upper ends to the respective ones of said line engaging members and adapted for connection at their lower ends to spaced portions of a clothespin bag or the like.

2. A hanger for supporting a clothespin bag or the like from an elongated horizontal element such as a clothesline consisting of a pair of spaced substantially vertical elongated relatively rigid members adapted at their lower ends for connection to a clothespin bag or the like and bent in their upper portions in a common direction to form upwardly and rearwardly extending diagonal portions, the upper portion of each of said diagonal portions being bent rearwardly and downwardly to form an inverted hook for engaging a horizontal elongated element, the free end portion of said hook being bent inwardly to underlie said hook and then upwardly to extend toward the inner side of said diagonal portion, said upwardly extending portion terminating at its upper end such a distance inwardly and downwardly of said diagonal portion that said elongated horizontal element may be passed between said upper end and said diagonal portion, the diagonal portions, hook portions, hook underlying portions and upwardly extending portions of the respective members being disposed in respective planes substantially normal to an elongated horizontal element upon which said hanger is hung.

JOHN FRITIOF LEONARDSON.
